UNITED STATES PATENT OFFICE.

ISRAEL MARMORSTEIN AND HENRY STONE, OF NEW YORK, N. Y.

SAFETY-LOCK FOR RIBBONS, BRACELETS, BELTS, AND OTHER SIMILAR ARTICLES.

1,303,704.

Specification of Letters Patent.

Patented May 13, 1919.

Application filed February 24, 1919. Serial No. 278,665.

To all whom it may concern:

Be it known that we, ISRAEL MARMORSTEIN and HENRY STONE, both residents of the city of New York, State of New York, the said 5 HENRY STONE a citizen of the United States and the said ISRAEL MARMORSTEIN a native of Hungary, (who has filed his first papers for citizenship of the United States,) have made certain new and useful Improvements 10 in Safety-Locks for Ribbons, Bracelets, Belts, and other Similar Articles; and we hereby declare the following specification to be a description of the same, reference being had to the accompanying drawings.

15 This invention relates to a construction of slide and lock which will permit the lengthening of ribbons such as are used for watch guards and secure the parts at any desired position. It is also adapted for use 20 with belts, bracelets, and other similar articles where a ready means of lengthening and shortening is desired.

The object is to provide a safety lock at the different adjustments in length, combined with ready means of shifting the locking device.

Figure 1 is a view of the lock in position on a strip of braid;

Fig. 2 is a view of the lock separate from 30 the braid;

Fig. 3 is a plan view of the under locking plate;

Fig. 4 is a separate view of the slide and Fig. 5 is a side elevation of Fig. 1.

35 The slide portion A, has three bars *a*, *b*, and *c* leaving two slits through which the braid B or buckle strap will pass. The central bar has two studs, *e*, *e*, projecting from it and these studs have heads slightly larger 40 than the shanks. The slide piece A is curved so the braid will be retarded in passing through the slits.

C and C¹ form the portion to be secured to an end of the braid B, and combined with 45 the slide A, secures it at various lengths.

The two plates C, and C¹, are hinged to-

gether at *h*, and the plate C, is provided with a slot *i*, to which an end of the braid is attached.

The plate C, is pierced with the keyhole 50 shaped openings *k*, *k*¹ which register in position to fit over the studs *e*, *e*.

The larger part of the openings *k*, *k*¹, is the same size as the head of the studs, the reduced portion of the openings being contracted to the same width as the shanks.

55 The locking or folding plate C¹, has two circular openings *o*, *o*, of the size of the heads of the studs *e*, *e*. These openings are located so that when the studs reach the end 60 of the contracted portion of the keyhole slots and the plate C¹ is folded down the heads of the studs will be received in them.

On the edge of the plate C¹, opposite the hinge is a projecting clasp *p*, which holds 65 the two plates C and C¹, together under ordinary pressure.

When the two plates of the lock are closed with the studs of the slide, in position in the holes of the plate C¹, the ends of the studs 70 are flush with the face of the plate.

It will be understood that changes of the parts and the number of studs and holes may be made without departing from the spirit 75 of our invention.

Having described our new and improved lock, what we claim as our invention and desire to secure by Letters-Patent is:—

80 A slide lock of the class described comprising a slide with two slit openings one on each side of a central bar carrying two headed studs, a hinged securing piece formed of two plates one of which plates is pierced with locking slots to receive and confine the said studs and the other hinged plate with 85 openings adapted to receive and hold the heads of said studs in their locked position, substantially as and for the purposes shown and described.

ISRAEL MARMORSTEIN.
HENRY STONE.
